UNITED STATES PATENT OFFICE.

SAMUEL STEINECKE, OF BROOKLYN, NEW YORK, ASSIGNOR TO CHRISTIAN A. SCHMIDT, OF HOBOKEN, NEW JERSEY.

DESIGN FOR TRIMMING.

SPECIFICATION forming part of Design No. 17,841, dated October 25, 1887.

Application filed September 8, 1887. Serial No. 249,177. Term of patent 14 years.

To all whom it may concern:

Be it known that I, SAMUEL STEINECKE, of Brooklyn, in the county of Kings and State of New York, have invented a new and original 5 Design for Gimp, of which the following is a specification, reference being made to the accompanying drawing, in which a face view of a piece of my newly-designed gimp is shown.

The leading feature of my design consists in 10 serpentine lines running in the direction of the length of the gimp, which serpentine lines are crossed at intervals by transverse lines, the transverse lines extending over the different serpentine lines alternately.

15 A is the center of the gimp; B B, the heading along the longitudinal edges.

C C C C are serpentine or wave lines—that is, lines that gradually approach and leave the longitudinal central line of the gimp.

20 D D are transverse lines extending over the serpentine lines C, the transverse lines D D of two adjacent serpentine lines C alternating—that is to say, a transverse line D extends across one serpentine line C midway between 25 the transverse lines D crossing the other serpentine lines C. The transverse lines D also

cross those serpentine lines C nearest the longitudinal central line of the gimp at those points of the serpentine lines farthest from the longitudinal central line; and it thus follows, 30 as the transverse lines on the serpentine lines alternate, that the transverse lines cross the outer serpentine lines—that is, the lines nearest the edge of the gimp—at those points of the said outer serpentine line nearest the longitudinal central line of the gimp. 35

Having thus described my design, I claim as new and desire to secure by Letters Patent—

The design for gimp, substantially as herein shown and described, the same consisting of 40 the body, headings, serpentine lines running in the direction of the length of the gimp, and transverse lines crossing the serpentine lines alternately.

In testimony that I claim the foregoing as 45 my invention I have signed my name in presence of two subscribing witnesses.

SAMUEL STEINECKE.
